UNITED STATES PATENT OFFICE.

CAROLINE E. TRACY, OF DETROIT, MICHIGAN.

CURTAIN-STRETCHER.

1,388,078.

Specification of Letters Patent. Patented Aug. 16, 1921.

Application filed November 5, 1920. Serial No. 422,032.

To all whom it may concern:

Be it known that I, CAROLINE E. TRACY, a citizen of the Dominion of Canada, residing at Detroit, in the county of Wayne and 5 State of Michigan, have invented new and useful Improvements in Curtain-Stretchers, of which the following is a specification.

This invention relates to devices for stretching lace curtains and the like and has 10 for its object the provision of a frame which is ordinarily in knock down condition and which may be quickly and easily set up and adjusted to hold curtains of any size and which is also additionally adjustable where- 15 by to stretch lace bed spreads and other similar articles which are not of the same relative proportions as are window curtains.

An important object is the provision of a device of this character in which the side 20 and end members of the frame are so connected that all the upper edges will be absolutely flush whereby curtains engaged upon pins projecting above the upper edges of the sides and ends will not have any tendency 25 to pull off.

Another object is the provision of a device of this character in which ordinary adjustment within reasonable limits may be made entirely without the manipulation of 30 any bolts, screws, or the like, an important feature being that there is a total absence of any bolts or other securing members of a like nature at any of the corners.

Another object is the provision of a device 35 of this character which carries its own legs which are normally in folded position but which are extended when the use of the device is desired, thereby obviating the necessity for standing the frame upon edge as 40 is the common practice, or of laying the frame across the backs of chairs as is another make-shift arrangement.

An additional object is the provision of a device of this character which will be simple 45 and inexpensive in manufacture, highly efficient in use, a great labor saver, durable in service, and a general improvement in the art.

With the above and other objects and ad- 50 vantages in view, the invention consists in the details of construction to be hereinafter more fully described and claimed and illus- trated in the accompanying drawings in which—

55 Figure 1 is a plan view of my curtain stretcher in position set up ready for use, Fig. 2 is a side elevation,

Fig. 3 is an end view,

Fig. 4 is a detail longitudinal sectional view through one of the sides, and 60

Fig. 5 is a detail perspective view showing two meeting ends disconnected.

Referring more particularly to the drawings, I have shown my device as comprising two sides broadly indicated by the numeral 65 10, and two ends designated broadly by the numeral 11. Each side 10 consists of a bar 12 and a bar 13, formed preferably of wood and of any desired length within reasonable limits. The bars 12 and 13 are overlapped, 70 as clearly shown, and are provided with elongated registering slots 14 whereby they may be adjusted, bolts 15 passing through these slots and being provided with wing or other nuts 16. By this construction it 75 will be seen that each side 10 is longitudinally extensible. The bar 13 is reduced in thickness throughout a portion of its length, as indicated at 17. The end of the bar 12 is bifurcated to provide spaced arms 18 which 80 are each provided upon their under edges with a pair of notches 19. The end of the bar 13 is likewise bifurcated to form arms 20 and each arm 20 is formed on its lower edge with a series of similar notches 21. Se- 85 cured upon the bars 12 and 13 and extending upwardly therefrom are the usual pins 22 upon which the curtain to be stretched, is engaged.

Each of the ends 11 comprises a bar 90 formed at one end in its upper edge with a pair of notches 23 adapted to be engaged with either pair of the notches 19 of the side bar 12. The end 11 has its other end 95 formed with a series of notches 24 within any one of which may be engaged a pair of notches 21 in the bar 13. These mating notches have their bottoms inclined, as shown, so as to form more efficient retaining means to prevent disengagement of the 100 bars when connected as above described. The ends 11 are likewise provided on their tops with the usual pins 25 upon which the curtain or other article to be stretched may 105 be engaged.

Each end 11 is provided with a pair of hinged legs 26 and each side is also provided with a single hinged leg 27 and all of these legs are foldable to lie against the undersides 110 of the associated pairs and are provided with braces 28 whereby they may be held in extended position.

In the use of the device the legs are of course swung downwardly into extended po-

sition and the notched ends of the side and end bars are brought together and engaged, it of course being necessary that the proper notches be engaged to make the frame of the required size corresponding to the lace curtain, bed spread, or the like to be stretched. The article to be stretched is then hooked onto the pins in the usual manner. In case it is necessary to stretch something of unusual length, it is apparent that by loosening the nuts 16 the bars 12 and 13 may be extended, the longitudinal slots permitting the necessary sliding movement. It is also apparent that the plurality of slots in the series 24 on each end bar 11 provides for wide variation in the width of the frame so that the device may be used for stretching lace bed spreads or the like which are wider than window curtains.

From the foregoing description and a study of the drawings it will be apparent that I have thus provided a simply constructed and consequently inexpensive curtain stretcher in which all the bars lie in the same plane or substantially so so that there will be no inequality at the corners which might result in causing the curtain to pull from the holding pins. The device is easily set up and the essential adjustments may be made without the use of any clamping bolts or screws, a feature highly advantageous inasmuch as the presence of such bolts frequently causes rust spots upon the article being stretched.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A curtain stretcher comprising a rectangular frame including end bars, each formed in its upper edge at one end with a notch and at its other end with a plurality of notches, said frame including pairs of slidably connected side bars having their inner portions relatively thin and having their outer portions downwardly thickened, the thickened portion at one end of the slidably connected side bars being formed with an upwardly extending notch engageable with in a selected one of said second named notches, the thickened portion at the other end of the slidably connected pair of bars being formed with a series of upwardly extending notches, a selected one of which may be engaged within said first named notch, legs hingedly connected with the end of the frame and legs pivotally connected with the intermediate portions of the side bars and a series of upwardly extending pins on the side bars and end bars.

In testimony whereof I affix my signature.

Mrs. CAROLINE E. TRACY.
